185,490

HAND DRYER FOR BOWLING LANES OR SIMILAR ARTICLE

Glenn L. Cota, Clifton, Ill., assignor to The Chicago Hardware Foundry Company, North Chicago, Ill., a corporation of Illinois

Application May 26, 1958, Serial No. 51,082

Term of patent 3½ years

(Cl. D4—3)

FIG. 1

FIG. 2

Figure 1 is a plan view of my hand dryer for bowling lanes or similar article, showing my new design; and

Figure 2 is a side elevational view of the hand dryer for bowling lanes or similar article of Figure 1.

I claim:

The ornamental design for a hand dryer for bowling lanes or similar article, substantially as shown.
